UNITED STATES PATENT OFFICE.

FRED L. PEARSON, OF SIOUX CITY, IOWA.

LOCKING-VALVE.

1,304,506.

Specification of Letters Patent.

Patented May 20, 1919.

Application filed March 29, 1917. Serial No. 158,472.

To all whom it may concern:

Be it known that I, FRED L. PEARSON, a citizen of the United States, and a resident of Sioux City, in the county of Woodbury 5 and State of Iowa, have invented certain new and useful Improvements in Locking-Valves, of which the following is a specification.

The present invention relates to locking 10 valves for controlling fluid passages.

The invention has for its primary object the production of a valve embodying an improved key-controlled lock for positively locking the valve.

15 Another object of the invention is the production of an improved key-controlled locking valve simple and inexpensive in construction yet thoroughly dependable and particularly adapted to be interposed in the 20 passage between the manifold and combustion chambers of the engine of a motor-vehicle to prevent theft or operation of the vehicle by unauthorized persons.

Still a further object of the invention is 25 the production in a motor-vehicle of a locking valve adapted to be mounted under the hood, and adapted to be operated without raising the hood.

The invention contemplates, broadly, 30 mechanism including a valve casing having an induction opening and inclosing a sliding valve adapted to open and close the said opening. The valve is provided with an improved form of lock which positively prevents movement of the valve except by use 35 of the particular key provided therefor, all of which will be clearly understood from the following description, reference being had to the accompanying drawings, which 40 form a part of this application and in which like characters of reference indicate corresponding parts throughout the several views, of which,—

Figure 1 is a transverse section of the preferred embodiment of the device;

Fig. 2 is a longitudinal section of the same;

Fig. 3 is an enlarged horizontal section of the valve taken on the line 3—3 of Fig. 1;

50 Fig. 4 is an enlarged transverse section of the lock taken on the line 4—4 of Fig. 3;

Fig. 5 is a side elevation of a motor vehi-

cle engine and its hood equipped with the device of my invention, the hood being open; Fig. 6 is a similar view with the hood 55 closed; and

Fig. 7 is a plan of the key.

Although, I have illustrated and herein-after described the preferred embodiment of the invention, I would not be understood as 60 being limited to the specific structure chosen for illustration, for various alterations and modifications in the details of construction and arrangement of parts may be made without departing from the spirit and scope 65 of the invention as defined in the appended claims.

Referring, now, to the illustrations, 8, is the valve casing preferably cylindrical and provided with an induction opening, 9. 70 Within the casing is a segmental valve, 10, which conforms to the curvature of the casing and is carried between disks, 11, positioned adjacent the opposite ends of the casing. Above the valve the disks are interconnected by or formed integrally with a block, 12, which serves to hold the disks in their proper relation and also serves as a cover for the locking mechanism as will presently appear.

80 The front disk engages an internal shoulder, 13, of the casing and the opposite end of the casing is provided with a cover preferably consisting of a plate of yieldable sheet metal, 14, dished outwardly and inwardly 85 depressed at its center to impinge the center of the adjacent disk to hold the companion disk firmly against the shoulder 13, to prevent leakage of fluid between the said shoulder and disk.

90 The casing is preferably provided on opposite sides with short flanged outlet pipes, 15, adapted to be interposed in the horizontal portion of the usual manifold, 16, of the engine. The induction opening, 9, is also 95 preferably a short flanged pipe to which the carbureter, 17, may be connected. In order to obviate lifting the hood, 18, to afford access to the valve, I provide in the hood a hand-hole, 19, normally closed by a small 100 door, 20, hinged or otherwise suitably secured on the hood to open and close the said hole.

The front disk is provided with a suitable

handle, 21, by which the disk may be turned within the casing to slide the valve between its opened and closed positions. The valve is shown in Figs. 1 and 2 as closing the induction opening in which position it is securely locked by mechanism carried by the valve. The lock consists preferably of one or more pairs of plungers, 22, slidably inclosed within a recess, 23, in the valve and adjacent the block, 12. The plungers move alternately in opposite directions each with respect to its mate, the adjoining faces of the plungers being cut away and provided with rack teeth, 24, intermeshed with pinions 25, fixed on spindles, 26, rotatably mounted in the body of the valve.

Means are provided for automatically retracting the plungers and holding them yieldably in their extended positions as clearly shown in Figs. 1 and 3. This means preferably consists of coil springs, 27, each having one end secured to the valve and its opposite end to the spindle. The inner end of one plunger of each pair is tapered as at 28, and normally extends into a key hole, 29, disposed laterally to the plungers. 30, is the key which is designed to slide longitudinally into the key hole and its end is tapered as at 31, to coact with the tapered ends of the plungers to force the latter outwardly as the key is inserted. The key is provided in its sides with tapered notches, 32, to receive the tapered ends of the plungers, the said notches being sufficiently deep to hold the plungers so that the outer ends of all are flush, as shown in dotted lines in Fig. 3.

The taper-ended plungers are preferably of different lengths, thereby requiring the respective notches, 32, to be of correspondingly different depths. The casing wall is recessed, as at 33, to receive the plunger and thereby prevent rotation of the valve. It is evident that if the notches, 32, which 45 coact with the tapered ends of the plungers are too shallow, that the said plungers will be forced outwardly into engagement with the sockets or recesses, 33. Likewise if the notches are too deep the said plungers will 50 not be forced outwardly far enough to withdraw the companion plungers from the recess.

Therefore, it is clear that this construction permits of a wide variation in keys 55 and, in practice, the device may be so constructed that a key will open no lock except the particular one for which it is intended. It is evident that the number of pairs of plungers may be varied as desired 60 by the manufacturer.

In opening the lock it is clear, that it is only necessary to thrust the key inwardly and through the medium of the handle 21, the valve may be rotated a half revolution 65 to the open position indicated in dotted

lines in Fig. 1, in which position the plungers will be received in a recessed part, 34, to lock the valve in its open position and permit removal of the key.

As previously stated it is not necessary to 70 raise the hood to gain access to the valve as it is only necessary to open the small door 20, to permit insertion and removal of the key for operation of the valve.

Having thus described my invention what 75 I claim as new and desire to secure by Letters Patent of the United States, is,—

1. A locking valve comprising a casing member having an opening therein for the passage of fluid, a valve member movable within the casing to open and close the opening, and a lock carried by one of said members including a plurality of pairs of plungers each movable in opposite directions alternately with respect to its mate, 80 one plunger of each pair being normally engaged with the other of said members to prevent movement of the valve member, and the other plunger of each pair being key-controlled and operable to withdraw its 85 mate from the engaged member.

2. A locking valve comprising a casing member having an opening therein for the passage of fluid, a valve member movable within the casing to open and close the 95 opening, and a lock carried by one of said members including a plurality of pairs of plungers, each movable in opposite directions alternately with respect to its mate, one plunger of each pair being normally 100 yieldably engaged with the other of said members to prevent movement of the valve member, and the other plunger of each pair being key-controlled and operable to withdraw its 105 mate from the engaged member.

3. A locking-valve comprising a casing having an opening therein for the passage of fluid, a valve movable within the casing to open and close said opening, and a lock carried by the valve including a plurality of 110 pairs of plungers, each movable in opposite directions alternately with respect to its mate, one plunger of each pair being normally yieldably engaged with the casing to prevent movement of the valve, and the other plunger of each pair being key-controlled and operable to withdraw its mate from 115 engagement with the casing.

4. A locking-valve comprising a casing having an opening therein for the passage 120 of fluid, a valve movable within the casing to open and close the opening, and a lock carried by the valve including a plurality of pairs of plungers, each movable in opposite directions alternately with respect to 125 its mate, the plungers being normally extended in opposite directions with one plunger of each pair engaged with the casing to prevent movement of the valve, and the other plunger of each pair being operable 130

when moved a predetermined distance to withdraw its mate from the casing and when moved farther than the predetermined distance to engage the casing to prevent 5 movement of the valve.

5. A locking-valve comprising a casing having an opening therein for the passage of fluid, a valve movable within the casing to open and close the opening, and a lock 10 carried by the valve including a plurality of pairs of plungers, each movable in opposite directions alternately with respect to its mate the plungers being normally extended in opposite directions with one plunger 15 of each pair engaged with the casing to prevent movement of the valve, and the other plunger operable when moved a predetermined distance to withdraw its mate from the casing, and when moved farther 20 than the predetermined distance to engage the casing to prevent movement of the valve, and a key operable to move the last described plungers to said predetermined distances.

25 6. A locking valve comprising a casing having an opening therein for the passage of fluid, a valve movable within the casing to open and close the opening, and a lock carried by the valve including a plurality of 30 pairs of plungers, each movable in opposite directions alternately with respect to its mate, the plungers being normally extended in opposite directions, with one plunger of each pair engaged with the casing to prevent 35 movement of the valve, and the other plunger operable when moved a predetermined distance to withdraw its mate from the casing and when moved farther than the predetermined distance to engage the 40 casing to prevent movement of the valve, the last described plungers of the pairs being of different lengths, and a key operable to move the latter plungers said predetermined distances.

45 7. A locking valve comprising a casing having an opening therein for the passage of fluid, a valve movable within the casing to open and close the opening, and a lock carried by the valve including a plurality of 50 pairs of plungers, each movable in opposite directions alternately with respect to its mate, the plungers being normally extended in opposite directions with one plunger of each pair engaged with the casing to prevent 55 movement of the valve and the other plunger operable when moved to a predetermined position to withdraw its mate from the casing and when moved farther than the predetermined position to engage the 60 casing to prevent movement of the valve, the extended ends of the latter plungers of each pair being tapered, a key operable to move the latter plungers to said positions and provided with notches to receive said 65 tapered ends and hold the plungers in said

positions, and means for retracting the plungers.

8. A locking-valve comprising a casing having an opening therein for the passage of fluid, a valve movable within the casing to open and close the opening, and a lock carried by the valve including a plurality of pairs of plungers, the adjacent sides of the mates being toothed, pinions between and intermeshed with the plungers to move the plungers alternately in opposite directions, each with respect to its mate and yieldable means holding the plungers normally extended with one plunger of each pair engaged with the casing to prevent 70 movement of the valve, and the other plunger of each pair being key operated to withdraw its mate from the casing.

9. A locking valve comprising a casing having an opening therein for the passage of fluid, a valve movable within the casing to open and close the opening, and a lock carried by the valve including a plurality of pairs of plungers, the adjacent sides of the mates being toothed, pinions between and intermeshed with the plungers to move the plungers alternately in opposite directions, each with respect to its mate, yieldable means holding the plungers normally extended with one plunger of each pair engaged with the casing to prevent movement of the valve, and the other plunger of each pair being movable to a predetermined position to withdraw its mate from the casing, and adapted when moved beyond said position to engage the casing to prevent movement of the valve, and a key operable to move the last described plunger of each pair to said positions.

10. A locking-valve comprising a casing having an opening therein for the passage of fluid, a valve movable within the casing to open and close the opening, and a lock carried by the valve including a plurality of pairs of plungers, the adjacent sides of the mates being toothed, pinions between and intermeshed with the plungers to move the plungers alternately in opposite directions, each with respect to its mate, yieldable means holding the plungers normally extended with one plunger of each pair engaged with the casing to prevent movement of the valve, and the other plunger of each pair being movable to a predetermined position to withdraw its mate from the casing, and operable when moved beyond said position to engage the casing to prevent movement of the valve, the latter plungers of the pairs being of different lengths and having their extended ends tapered, and a key movable transversely of and adapted to move the last described plungers, said key being provided with tapered notches to receive the tapered ends and hold the plungers in said positions.

11. A locking-valve comprising a casing having a circular wall having an opening for the passage of fluid, a closed end and an open end having an internal shoulder, disks 5 rotatable within the casing and adjacent the ends thereof, yieldable means at the closed end operable to hold the farther disk against the shoulder, a segmental valve carried between the disks and slidable adjacent the wall to open and close the opening by rotating the disks, and a key-controlled lock 10 to normally prevent rotation of the disks.

12. A locking-valve comprising an open-ended casing having a circular wall, having 15 an opening for the passage of fluid, an in-

ternal shoulder at one end of the casing, a plate of yieldable material covering the other end, disks rotatable within the casing and adjacent the ends thereof, one of said disks being engaged by the plate to force 20 the opposite disk against said shoulder, controlling means on the latter disk, a segmental valve carried between the disks and slidable adjacent the wall to open and close the opening by rotation of the disks, and a 25 key-controlled lock to normally prevent rotation of the disks.

In testimony whereof, I have hereunto set my hand this 8th day of March, 1917.

FRED L. PEARSON.
